[57] **CLAIM**

The ornamental design for a balancing machine for
vehicle wheels, as shown.

DESCRIPTION

FIG. 1 is a top, front, and right side perspective view of
a wheel balancing machine for vehicle wheels showing
my new design;

FIG. 2 is a front elevational view;

FIG. 3 is a left side elevational view;

FIG. 4 is a right side elevational view; and

FIG. 5 is a top plan view thereof.

FIG. 5
